UNITED STATES PATENT OFFICE.

JAMES JEWELL, OF GRANDVILLE, MICHIGAN, ASSIGNOR OF ONE-HALF TO
GEORGE FRAZER AND JOHN J. FIDLER, BOTH OF SAME PLACE.

PIPE-WRENCH.

SPECIFICATION forming part of Letters Patent No. 292,175, dated February 5, 1884.

Application filed August 27, 1883. (No model.)

To all whom it may concern:

Be it known that I, JAMES JEWELL, of the village of Grandville, Kent county, Michigan, have invented a new and useful Improvement in Pipe-Wrenches, of which the following is a specification, reference being had to the accompanying drawings.

My invention relates to the construction of a pipe-wrench designed for the use of gas-fitters, plumbers, and others having occasion to work iron pipes, and may be made of any suitable size or of any suitable material.

In the drawings, Figure 1 is a side elevation, and Fig. 2 is an end view, of the strap E.

Similar letters of reference refer to corresponding parts throughout the several figures.

The letter A represents the main toothed jaw of the wrench, and F is the shank thereof, having teeth upon its upper surface. The outer end of this shank forms the handle of the implement.

B is a block having on its under surface teeth which mesh with the teeth of the shank. This block is socketed, as shown, and it is provided with a shoulder, b, and extension b'.

E represents the loop, which is passed on the shank of the wrench, and it is provided with a pin, s, by means of which the extension b' of the block B is pivoted thereto, whereby said block may be moved backward or forward on the shank with the loop.

The letter C denotes the gripping-jaw, pivoted to a pin, a, in the upper end of the loop, and seated in the socket of the block B, and it is provided with a shoulder, c, which abuts

against the shoulder b of the block when pressure is brought to bear upon the jaws A C, thus relieving the pin a from strain. This jaw is also removable backward or forward with the block B by means of its being pivoted to the loop. The toothed block is held in contact with the teeth of the shank by means of the wedge D engaging the loop and under surface of the shank, and it is provided with a downward projection, i, to prevent its slipping out from the loop. I attach importance to the fact that the under or gripping jaw, C, is provided with a shoulder to engage the shoulder of the block, whereby the strain is upon the teeth of the said shoulder and against the shank by the pressure of the teeth on the block.

Having thus described my invention, I claim as new and desire to secure by Letters Patent—

The pipe-wrench herein described, consisting of the toothed jaw A, having the toothed shank F, the toothed block B, pivoted to the pin s of the loop E, and having the shoulder b and socket, as shown, the jaw C, pivoted to the pin a of said loop, and provided with a shoulder, c, adapted to abut against the shoulder of the block, whereby strain is relieved on the pin a, and the wedge D, for securing the block and shank together, as shown and described.

JAMES JEWELL.
